UNITED STATES PATENT OFFICE.

JOHN MAXWELL, OF AMSTERDAM, NEW YORK.

IMPROVEMENT IN MEANS FOR OILING KNITTING-MACHINE BURRS.

Specification forming part of Letters Patent No. 44,437, dated September 27, 1864.

To all whom it may concern:

Be it known that I, JOHN MAXWELL, of Amsterdam, county of Montgomery, and State of New York, have invented a new and Improved Method of Lubricating Knitting-Burrs; and I do hereby declare that the following is a full, clear, and exact description thereof, reference being had to the accompanying drawings, making a part of this specification, in which—

Figure 1 is a top view of a knitting-burr having my invention applied to it. Fig. 2 is a diametrical section through Fig. 1. Fig. 3 is a view of the axis around which the burr revolves.

Similar letters of reference indicate corresponding parts in the three figures.

The object of my invention is to provide for keeping the axes of knitting-burrs always well oiled with clean oil and intact from dust and fuzzy substances, which so often clog and cause a derangement of the knitting machinery.

The nature of my invention consists in a tubular axis, around which the burr revolves, and from which it receives its oil, in conjunction with a cap which is affixed to the burr, so as to constitute a cover for the upper end of said axis, as will be hereinafter described.

To enable others skilled in the art to make and use my invention, I will describe its construction and operation.

In the accompanying drawings, A represents a knitting-burr, which may be made in the usual or most improved manner.

B represents the axis around which the burr A revolves, which has a shoulder formed on it at *a*, upon which the burr is supported, as shown in Fig. 2. Above this shoulder *a* the axis is made tubular, and the chamber thus formed is to receive cotton or other suitable spongy substance, which is to be saturated with oil that is supplied to the burr through an orifice, *b*. The cotton will absorb the oil put into the tubular axis and supply it in small quantities to the burr. Surrounding

this axis B, and forming a part of the burr, is a tube, *c*, the ends of which project short distances from the upper and lower surfaces of the burr. The lower end of this tube or bushing rests upon the shoulder *a* of the axis, and the upper end receives over it a pivoted cap, *g*, which is connected to the upper face of the burr and turns with it. As this cap *g* is pivoted to the burr in such relation to the upper end of the tubular axis as to cover it closely and exclude all dust, &c., it can be turned aside at any time and the oil-chamber supplied with fresh oil without removing the burr from its axis.

The cap *g* is made of such size as to completely cover the end of the tube *c*; hence nothing can get in around the axis B through the upper end of this tube *c*. Instead of a pivoted cap, a sliding cap or cover may be used, in which case it will be made so as to cover the tube *c* and exclude dust, &c.

By this simple arrangement the difficulties attending oiling and keeping the axes of knitting-burrs oiled are removed and neither dust nor the "flyings" escaping from the yarn will in any way interfere with the free running of the burr.

Having thus described my invention, what I claim as new, and desire to secure by Letters Patent, is—

1. The application of a movable cover, *g*, to a knitting-burr having a tubular oil-supplying axis, about which the burr revolves, substantially as described.

2. The combination of a cap, *g*, tube *c*, and tubular spindle or axis B with a knitting-burr, substantially as described.

3. The combination of shoulder *a* and tubular axis B with a knitting-burr having a cap applied to it for closing said axis, substantially as described.

JOHN MAXWELL.
